UNITED STATES PATENT OFFICE.

JOHANN CARL GRÄBNER AND HENRI RUPERTI, OF KUPFERHAMMER, NEAR BRACKWEDE, GERMANY.

STEAM-ACTUATED VALVE.

SPECIFICATION forming part of Letters Patent No. 434,335, dated August 12, 1890.

Application filed February 21, 1889. Serial No. 300,790. (No model.)

To all whom it may concern:

Be it known that we, JOHANN CARL GRÄBNER, a subject of the King of Bavaria, and HENRI RUPERTI, a subject of the Grand Duke 5 of Mecklenburg, residing both at Kupferhammer, near Brackwede, Westphalia, Prussia, Germany, have invented new and useful Improvements in Steam-Actuated Valves, of which the following is a specification.

10 This invention relates to cylinder-and-piston motor-engines, and its object is to dispense with the devices heretofore employed for distributing the motor-fluid, and to effect the distribution of the motor-fluid directly 15 from the source of supply alternately to the ends of the cylinder and piston.

The invention consists in the novel construction, arrangement, and combination of parts, all as hereinafter described and claimed.

20 Reference is to be had to the accompanying drawings, forming a part of this specification, wherein similar letters of reference indicate corresponding parts in all the views.

Figure 1 is a vertical longitudinal section 25 through the cylinder of the engine and the distributing device, taken on the line C D in Fig. 3. Fig. 2 is a horizontal section through the cylinder of the engine, taken on the line A B in Fig. 1; and Fig. 3 is a vertical trans- 30 verse section through the cylinder of the engine and the distributing device, taken on the line C D in Fig. 1.

The piston B in the engine-cylinder A is hollow and in continuous communication 35 through an opening b, formed in the bottom wall of the cylinder, with the steam-inlet pipe a, so that there is always a full pressure of steam in the piston. The hollow space of the piston thus serves in substitution of the 40 slide-box usually employed and arranged beside the engine-cylinder. A piston-slide h, having annular portions h' and h'', is fitted in a second cylinder mounted upon the cylinder A, and the space of said slide-cylinder 45 communicates with the ends of the engine-cylinder through live-steam ports formed in the walls of the slide-cylinder and registering with live-steam ports i i' and m m', formed in the walls of said engine-cylinder. An exhaust 50 port f, formed in the side walls of the engine-cylinder, at one end thereof, leads to an ex-

haust-port f'', formed in the walls of the slide-cylinder, and a similar exhaust-port f at the other end of the engine-cylinder, which is covered by the piston in Fig. 1, 55 leads to another exhaust-port f' in the wall of the slide-cylinder, both said exhaust-ports leading to an exhaust-pipe g, formed in the cylinder of the piston-slide. In the position of the piston and the piston-slide shown in Fig. 1 of the drawings the ports f and f'' and the space in front of the piston are connected with the exhaust-pipe g. When the piston and piston-slide are in a position opposite to that shown in Fig. 1, the other port f, the port f', 60 and the space behind the piston are in connection with said exhaust-pipe. Assuming the piston B to be at the end of its stroke to the left, as shown in Figs. 1 and 2, the steam arriving from the hollow space of the piston 70 and the port i, acting on the annular part h' of the piston-slide, drives the slide to the right, so that the port m is opened toward the slide, while the port m' is closed toward said slide, as shown in Fig. 1. In this position of the slide the exhaust-port f', which 75 is in communication with the space behind the piston, is closed toward the exhaust-pipe g, and the exhaust-port f'', which is in communication with the space in front of the piston, is opened toward the exhaust-pipe 80 g, and the live steam flows from the hollow piston behind the same and acts thereon to move it to the right. As the piston moves to the right, steam flows through a recess o, 85 formed in the walls of its cylinder behind the piston, until the edge 2 of the piston covers the edge 11 of the port m, for as the edge 2 of the piston passes over the edge 1 of the port i steam flows from the piston through 90 the port m, and thence through the cylinder, the piston-slide, and the port i behind the piston.

As above stated, the flow of steam from the piston behind the same is interrupted when 95 the edge 2 of the piston has passed over the edge 11 of the port m as the piston moves from the left to the right. The steam in front of the piston passes through the ports f and f'' to the exhaust-pipe g until the front edge 100 5 of the piston, as the latter moves to the right, passes over the port f—that is to say,

has closed said port—and after said port has been thus closed the compression of the steam in front of the piston will commence. When the piston has arrived at the end of 5 its stroke to the right—that is to say, when the edge 2' of the piston has passed over the edge 1' of the port i—the steam flowing from the piston will flow through the port i' and act on the annular part h'' of the piston-slide 10 and move said slide to the left—that is to say, in the direction opposite to that shown in Fig. 1. By this movement of the piston-slide the port m' is opened toward the slide, and the steam will flow from the piston in front 15 of the same in the other recess o and act to move the piston to the left until the edge 2' of the piston has passed over the edge 11' of the port m'. The steam then flows through the cylinder of the piston-slide and 20 the port i behind the piston, and flows thence through the port f', which is opened when the piston-slide reaches the end of its stroke to the left, and escapes through the exhaust-pipe g. These movements of the piston and 25 piston-slide are repeated at both ends of the engine-cylinder alternately by the alternate flow of the steam through the ports i m and i' m'. The ends of the piston-slide h carry 30 rods e and e', which in turn carry buffer-pistons d and d', borne upon by coiled springs on said rods and adapted to move in air-cylinders e and e' surrounding the pistons. The purpose of said buffer-pistons is to lessen 35 the shock of the piston-slide as the latter is suddenly moved by the steam from the left to the right, or vice versa, so that the slide will not strike with its ends against the covers k and k' of the cylinder.

It will be understood that the herein-described distributing device may be applied 40 as well to single as to double acting engines,

and to engines in which the steam operates either on one or both sides of the piston.

Having thus fully described our invention, what we claim, and desire to secure by Letters 45 Patent, is—

1. In a fluid-motor engine, the combination, with a cylinder A, having the steam-inlet opening b in its lower wall, the interior steam-passages o near its ends, the exhaust-ports f 50 in its side walls, and the live-steam ports i i' and m m' in its upper wall, of the piston B, fitted in said cylinder, having a hollow space in its interior in communication with the inlet-opening and the steam ports and passages in said cylinder, substantially as shown and described.

2. In a fluid-motor engine, the combination, with the cylinder A, having the inlet-opening b, steam-passages o, exhaust-ports f, live-steam 60 ports i i' and m m', and the hollow piston B in said cylinder, in communication with said inlet-opening and steam ports and passages, of a second cylinder mounted upon the cylinder A and in communication with the live-steam ports of said cylinder, and having exhaust-ports f' and f'' and an exhaust-pipe g in communication with the exhaust-ports of said cylinder, and a piston-slide h, fitted in said second cylinder, formed with the annular portions h' and h'', and carrying the buffer-pistons d and d' at its ends, substantially 65 as shown and described, for the purpose specified.

In testimony whereof we have signed our 75 names to this specification in the presence of two subscribing witnesses.

JOHANN CARL GRÄBNER.
HENRI RUPERTI.
